CLAIM

I claim the ornamental design for a boat-shaped receptacle, as shown and described.

DESCRIPTION

FIG. 1 is a top front isometric view of a boat-shaped receptacle showing my new design;

FIG. 2 is a bottom rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.
